2,629,336

AUTOMATIC TURNTABLE FOR MODEL RAILWAYS

Gerald S. Seidel, Norristown, Pa.

Application October 20, 1950, Serial No. 191,173

12 Claims. (Cl. 104—38)

1

This invention relates to automatic turntables for model electric railway systems.

It is the principal object of the present invention to provide a turntable for model electric railway systems which may be automatically moved to the desired position and stopped at that position.

It is a further object of the present invention to provide a turntable for model electric railway systems in which an improved character of control of the operation of the turntable is provided.

It is a further object of the present invention to provide an automatic turntable for model electric railway systems in which positive driving mechanism is provided, operable at a desired range of speeds, and in which the driving motor is provided with a brake for quick and exact stopping.

Other objects and advantageous features of the invention will be apparent from the specification and claims.

The nature and characteristic features of the invention will be more readily understood from the following description taken in connection with the accompanying drawings forming part hereof, in which:

Figure 1 is a top plan view of a portion of a model electric railway system having the turntable in accordance with the present invention installed therein;

Fig. 2 is an underneath plan view of the platform or movable table portion of the turntable;

Fig. 3 is a fragmentary sectional view taken approximately on the line 3—3 of Fig. 1;

Fig. 4 is a fragmentary view in perspective showing a preferred form of switch actuator employed in connection with the invention;

Fig. 5 is a fragmentary sectional view taken approximately on the line 5—5 of Fig. 3; and

Fig. 6 is a diagrammatic view illustrating the circuit connections for a preferred mode of actuation of the turntable.

It should, of course, be understood that the description and drawings herein are illustrative merely and that various modifications and changes can be made in the structure disclosed without departing from the spirit of the invention.

Like numerals refer to like parts throughout the several views.

Referring now more particularly to the drawings, the turntable in accordance with the present invention preferably includes a pit P and, movable therein as hereinafter explained, a table or platform T.

The pit P preferably is made as a box having a horizontal rectangular bottom wall or base 10, of non-conducting material such as wood, on which a circular mounting strip 11, of non-con-

2

ducting material, such as wood, is secured. The strip 11 has mounted thereon circular pit rail sections 12 and 12a, of electrical conducting material, separated by two diametrically opposite breaks 13 and 14, formed in any desired manner, such as by saw cuts, to interrupt the current flow, and maintain the desired polarity, as hereinafter explained. Surrounding the mounting strip 11, a circular wall 15 is provided, of any desired and preferably non-conducting material, terminating at its upper edge at a horizontal cover portion 16, preferably of wood or other suitable non-conducting material on which the rails of the track layout with which the turntable is employed may be secured. The pit P may also have vertical side walls 18 extending from the bottom wall 16 to the cover portion 16.

The cover portion 16 has mounted thereon spaced and insulated conducting rails constituting a yard track section TS1 with rails TS1a and TS1b, preferably has a roundhouse track section TS2 diametrically opposite thereto with spaced and insulated conducting track rails TS2a and TS2b, and may have a number of additional radially extending and oppositely disposed track sections, illustrated as TS3 to TS24, inclusive, each with corresponding spaced and insulated conducting rails TS3a and TS3b to TS24a and TS24b, inclusive.

For purposes of clarity certain of the subsidiary designations, such as those of the track rails and duplicated conductors have been omitted from the drawings.

The base 10, at the central portion thereof, is provided with a hollow post 20 which is secured in position by an upper nut 21 and a lower nut 22 in engagement with a threaded lower end 23 of the post 20. The post 20 is preferably of electrical conducting material and is adapted to have an electrical conductor 25 connected thereto and held in position by a nut 22a. The central opening in the post 20 is adapted to have an electrical conductor 26 extending therethrough, and insulated therefrom, with an insulated contact 27 at the upper end thereof. The base 10 is provided with a plurality of pins TP1 to TP24, inclusive, one for each track section TS, the pins TP being offset clockwise from the center of the track section TS at which the table T is to stop, as hereinafter pointed out. Each opposite pair of pins TP, is connected by a conductor 28, for purposes to be explained.

The table T preferably includes an upper relatively rigid wall portion 30, of non-conducting material and preferably formed of plywood or the like, beneath which a mounting plate 31 is provided, preferably of conducting material. At the central portion of the table T, and on the lower face of the mounting plate 31 a metallic bracket 32, is provided, having an offset lower portion 33,

with bifurcated ends 34 extending horizontally on opposite sides of the post 20 to prevent side-wise displacement. The bracket 32 holds a spring contact 35 in position, the spring contact 35 and bracket 32 being connected to the mounting plate 31 in electrical conducting relation and engaging the central post 20 for establishing a portion of an electric circuit.

On the mounting plate 31, a reversible electric motor 36 is provided, electrically connected to the plate 31 and having a drive shaft 37 on which a worm 38 is mounted. The worm 38 is in engagement with a gear 39 secured on a shaft 40 which is supported in brackets 41, the brackets 41 being secured to the mounting plate 31. The shaft 40 has secured thereto a worm 42 which is in engagement with a gear 43 secured on a driving shaft 44, the shaft 44 being carried in a bracket 45 secured to the mounting plate 31. A driving roller 46, for driving engagement with the pit rail 12 is secured to the shaft 44. The driving roller 46 may be of any desired insulating material, but is preferably formed of a suitable synthetic plastic material, and may if desired be of rubber, synthetic or natural, having a sufficiently resilient exterior face to frictionally engage with the pit rail 12.

Contiguous to the bracket 45, a spring contact 47 is provided for engagement with the pit rail 12, the contact 47 being insulated from the mounting plate 31 and having an electrical conductor 48 extending therefrom and upwardly through the wall 30.

At the opposite end of the table T, a bracket 50 is provided on the lower face of the mounting plate 31, having a roller 51, preferably of the same character as the roller 46, mounted therein. Contiguous to the bracket 50, a spring contact 52 is provided insulated from the plate 51, for engagement with the pit rail 12, and having an insulated electrical conductor 53 extending therefrom and upwardly through the wall 30.

On the upper horizontal face of the wall 30, spaced and insulated track rails 54 and 55 are provided, of electrical conducting material, to which the conductors 48 and 53 are respectively connected for energizing the rails 54 and 55, as hereinafter explained.

Adjacent the bracket 50, a bracket 60 is provided, on the lower face of the mounting plate 31 and electrically insulated therefrom, and having downwardly extending bracket arms 60a. Within the bracket arms 60a, a switch actuator 61, of conducting material is slidably mounted. The switch actuator 61 has an inner vertical end portion 62, and a horizontal terminal portion 63 which serves as a limit stop upon engagement with the inner bracket arm 60a. The switch actuator has an outer or free end 61a of flat V-shape for engagement with and movement by the pins TP, as hereinafter explained.

Secured to the mounting plate 31, a switch 64 is provided having normally closed contacts (not shown), controlled by a resiliently impelled switch operator 65, with which the end portion 62 is in engagement. A conductor 66, connected to the bracket 60 and to one of the contacts of the switch 64, extends to the motor 36, and a conductor 67, connected to the other of the contacts of the switch 64, extends to contact bracket 68 carried on the plate 31, and insulated therefrom, with which the contact 27 engages.

The motor shaft 37 is preferably provided with a brake collar 70 having a friction insert therein and an outwardly projecting screw 71 which is

adapted for tightening the friction insert against the shaft 37 and for abutment, upon rotation of the shaft 37 against the outer of the brackets 41.

In order to provide power for actuation of the motor 36 and for energization of the track rails, any suitable source S of electric energy, such as direct current or rectified alternating current is provided, to which a pair of power leads 72 and 73 is connected. One of the power leads, such as the lead 72, may, if desired, have an adjustable rheostat 74 inserted therein. The power leads 72 and 73 are preferably connected to a reversing switch RS for reversal of current polarity and direction of operation, as desired. The switch RS is connected by leads 72a and 73a to the central portion of a double pole double throw switch DRS from which power leads 74 and 75 extend. The power lead 74 is preferably connected to one of the sections of the pit rail, such as the section 12a, and the power lead 75 is preferably connected to the other pit rail section.

The conductor 74 is connected to the rail TS1b. A conductor 79 is provided connecting the rail TS1b to the opposite rail TS2b. A conductor 75 is provided, extending from the conductor 75 to the track rail TS1a, beyond an insulating break 78 in the rail, and a conductor 80 is provided connecting the opposite rails TS1a and TS2a. The opposite rails of the opposite track sections, such as TS3 and TS14, and TS4 and TS15, etc. are similarly connected.

The other contacts of the switch DRS have the conductors 25 and 26 connected thereto.

In order to control the selective movement of the table T and the energization of the track sections TS1 and TS24, inclusive, in pairs, a control switch CS is provided.

The control switch CS has a pair of banks of contacts indicated as A and B. The bank of contacts A preferably includes a contact arm 81 which is adapted to be connected by an annular contact bar 82 movable therewith, to all of a plurality of contacts AC1 to AC12, inclusive, except a selected one. The contact arm 81 is connected by a conductor 83 to the same contact of the switch DRS as that to which the conductor 25 is connected. The contacts AC1 to AC12, inclusive, are respectively connected, by conductors such as the conductor 84, to respective pairs of pins TP, the conductor 84 being shown as connected to pin TP1 (which is in turn connected to pin TP2 by its conductor 28).

The bank of contacts B preferably includes a contact arm 85 to which a conductor 86 extends from the contact of the switch DRS to which the conductor 75 is connected. The contact arm 85 is adapted to selectively engage one of a plurality of contacts BC1 to BC12, inclusive. The contacts BC1 to BC12, inclusive, are respectively connected by conductors such as the conductor 87, to one of the rails, such as the rail TS1a inwardly of the insulating break 78. The contact arms 81 and 85 are connected together for rotary movement by a shaft 88, having an operating and indicating knob or handle 89, at the front end thereof, and a position indicating dial 90, for indicating the position of the contact arms 81 and 85.

The mode of operation of the turntable will now be pointed out.

With power supplied from the power source S through the power leads 72 and 73 and the rheostat 74 and with a polarity as determined by the reversing switch RS, power will be sup-

plied to the switch DRS, and therefrom in accordance with the positioning of the arm of that switch.

If the switch DRS is positioned to the right (see Fig. 6) to energize the rails TS1a and TS1b of the yard track section TS1, a locomotive thereon will be advanced on the yard track section TS1 to a position beyond the insulating break 78 in the track rail TS1a. If it is desired to energize the track section TS1 this may be done by turning the shaft 88 to a position to bring the contact arm 85 into engagement with the contact BC1. The roundhouse track section TS2 will be simultaneously energized through the conductors 79 and 80. The energization and polarity of the rails 54 and 55 on the table T will be determined by the engagement of the contacts 47 and 52 with the respective sections of the pit rail 12. When the locomotive has been moved onto the rails 54 and 55, the energizing circuit to the rails may then, if turning of the table T is desired, be interrupted by movement of the switch DRS.

The circuit for energizing the motor 36, which includes the contacts AC1 to AC12, inclusive, and the conductors 25 and 26 is dependent upon the positioning of the switch DRS in the opposite position to that referred to above for track circuit energization.

If it is desired to move the table T, the switch CS is positioned to move the contact arm 81 to a position corresponding to that to which the table T is to be moved. In this connection it will be noted that a motor energizing circuit is set up through the conductors 25 and 26, which includes, in series therewith, the switch 64. The switch 64 is normally effective to permit energization of the motor 36 except when the switch actuator is in engagement with a de-energized pin TP.

With the motor 36 operated and turning the table T, as the switch actuator engages a pin TP it breaks the circuit through the switch 64, and if the pin TP is energized, an alternative energizing circuit is set up through the energized pin TP, the switch actuator 61, and conductor 66, to maintain the motor 36 energized. If a particular pin TP is unenergized, by reason of the positioning of the contact bar 82, the table T will stop at that location.

It will be noted that the switch RS permits of reversal of polarity of the motor energizing current so that, by selection of the direction of rotation, the table T may be turned in the direction required, i. e. clockwise or counterclockwise as the case may be, to bring it to the unenergized pin TP for the track section TS at which stopping is desired.

The rheostat 74 may be employed for regulating the speed of movement of the table T as well as the speed of movement of the train onto and from the track sections TS and the rails 54 and 55.

The brake collar 70 and its abutment and adjusting screw 71 effect instant stopping of the motor 36, if desired, and prevent overrunning of the table T, so that upon stopping of the table T, the rails 54 and 55 will be aligned with the rails of the particular track section TS at which the stop is made. The pins TP may be bent slightly if desired to provide a close stopping adjustment.

The brake collar 70 is not always necessary with the table T loaded but is desirable for operation without any locomotive on the tracks 54

and 55. The collar 70 must not be too tight or overheating of the motor 36 may occur with prolonged operation.

It will be noted that the switch actuator 61 has a loose fit in the bracket arms 60a, the lost motion thereby provided also facilitating stopping with the rails 54 and 55 in proper alignment with the rails of an appropriate track section TS.

10 When the table T has been moved to the desired position and has stopped it will remain in this position. Upon movement of the switch DRS to its initial energizing position, and with the switch RS positioned as desired to give the desired polarity, the locomotive will then be energized from the rails 54 and 55 to move onto the desired track section TS.

15 It will be noted that while only twelve positions are shown for the control switch CS it is possible to move the table T for delivery of the locomotive onto any one of twenty-four locations, this being possible by reason of the interconnection of opposite pins TP and the reversibility of the motor 36 which permits the approach to the appropriate unenergized pin TP corresponding to the selected delivery position from a direction such that it will not be necessary to strike the opposite and unenergized pin TP.

20 I claim:

25 1. In a turntable for model railway systems having a pit with track section rails leading thereto and a motor driven table with spaced rails thereon rotatable in said pit, the combination comprising connections to a source of electrical energy, a control member connected to said connections and having a plurality of contact positions, contact members for one of said contact positions connected to said motor, additional contact members for another of said contact positions connected to rails of the track sections, and a multiple position controller having members for determining the energization of the track actions and for determining the stopping location of said table.

30 2. In a turntable for model railway systems having a pit with track section rails leading thereto and a motor driven table with spaced track rails thereon rotatable in said pit, the combination comprising connections to a source of electrical energy, a polarity reversing member interposed in said connections, a control member connected to said connections having a plurality of contact positions, contact members for one of said contact positions connected to said motor, additional contact members for another of said contact positions connected to rails of the track sections, and a multiple position controller having contact members for determining the energization of the track sections and contact members for determining the stopping location of said table.

35 3. In a turntable for model railway systems having a pit with a pit rail therein and with track section rails leading thereto and a motor driven table with spaced track rails thereon rotatable in said pit, the combination comprising connections to a source of electrical energy, a polarity reversing member interposed in said connections, a control member connected to said connections having a plurality of contact positions, contact members for one of said contact positions connected to said motor, additional contact members for another of said contact positions connected to rails of the track sections, and a

multiple position controller having members for determining the energization of the track sections and track rails.

4. In a turntable for model railway systems having a pit with track section rails leading thereto and a motor driven table with spaced track rails thereon rotatable in said pit, the combination comprising connections to a source of electrical energy, a control member connected to said connections having a plurality of contact positions, contact members for one of said contact positions connected to said motor, additional contact members for another of said contact positions connected to rails of the track sections, and a multiple position controller connected to said motor and having members for determining the stopping location of said table.

5. In a turntable for model railway systems having a pit with pit rail sections therein and having track section rails leading thereto and a motor driven table with spaced track rails thereon rotatable in said pit, the combination comprising connections to a source of electrical energy, a control member connected to said connections and having a plurality of contact positions, and contact members for one of said contact positions connected to said pit rail sections, contact members on said table for engagement with said pit rail sections, and connections from said last named contacts to said track rails.

6. In a turntable for model railway systems having a pit with track section rails leading thereto and a motor driven table with spaced track rails thereon rotatable in said pit, the combination comprising connections to a source of electrical energy, a control member connected to said connections having a plurality of contact positions, contact members for one of said contact positions, circuit connections from said contact members to said motor including a central post in said pit.

7. In a turntable for model railway systems having a pit with energizable pit rail sections therein and with pairs of track rails leading thereto and a table with spaced rails rotatable on said pit rail sections in said pit, the combination comprising abutments in said pit corresponding to each of said pairs of track rails, contacts for engagement with said pit rail sections for energizing said spaced rails, a motor on said table, a driving connection from said motor to said pit rail sections, and means on said table and controlled by said abutments for effecting energization of said motor.

8. In a turntable for model railway systems having a pit with electrically separated energizable pit rail sections therein and with track rails leading thereto and a table with spaced rails rotatable on said pit rail sections in said pit, the combination comprising supports on said table for engagement with said pit rail sections, contacts for respective engagement with said pit rail sections for energizing said spaced rails with a predetermined polarity, a motor on said table, a driving connection from said motor to one of said supports, and circuit controlling means on said table for effecting energization of said motor.

9. In a turntable for model railway systems having a pit with track rails leading thereto and with abutment members therein and a table with spaced rails rotatable in said pit, the combination comprising means for selectively controlling the energization of said abutment members, a motor on said table, a driving connection from said motor for rotating said table, and circuit

controlling means on said table for effecting energization of said motor, including normally closed contacts operable upon engagement with a deenergized one of said abutment members for effecting deenergization of said motor.

10. In a turntable for model railway systems having a pit with track section rails leading thereto and a motor driven table with spaced track rails thereon rotatable in said pit, the combination comprising connections to a source of electrical energy, a control member connected to said connections having a plurality of contact positions, contact members for one of said contact positions connected to said motor, abutment members for each of said track sections carried by said pit, contacts carried by said table and actuated by said abutment members for interrupting the circuit to said motor, and a multiple position controller having circuit connections for selectively energizing said motor and thereby determining the stopping location of said table.

11. In a turntable for model railway systems having a pit with track section rails leading thereto and a motor driven table with spaced track rails thereon rotatable in said pit, the combination comprising connections to a source of electrical energy, a control member connected to said connections having a plurality of contact positions, contact members for one of said contact positions connected to said motor, abutment members for each of said track sections carried by said pit, contacts carried by said table and actuated by said abutment members for interrupting the circuit to said motor, and a multiple position controller having circuit connections for selectively energizing said abutment members to set up alternative energizing circuits therethrough and thereby determining the stopping location of said table.

12. In a turntable for model railway systems having a pit with diametrically opposite track section rails leading thereto and a motor driven table with spaced track rails thereon rotatable in said pit, the combination comprising connections to a source of electrical energy, a control member connected to said connections having a plurality of contact positions, contact members for one of said contact positions connected to said motor, abutment members carried by said pit for each of said track sections having diametrically opposite pairs electrically connected, contacts carried by said table and successively actuated by said abutment members for interrupting the circuit to said motor, bypass circuit connections for said contacts, and a multiple position controller having circuit connections for selectively energizing said abutment members and said bypass circuit connections, said controller having an energized connection to said abutment members thereby determining the stopping location of the table.

GERALD S. SEIDEL.
